No. 37,335.

Patented February 14, 1905.

UNITED STATES PATENT OFFICE.

BYRON B. GOLDSMITH, OF NEW YORK, N. Y.

DESIGN FOR A LEAD-PENCIL TIP.

SPECIFICATION forming part of Design No. 37,335, dated February 14, 1905.

Application filed December 22, 1903. Serial No. 186,261. Term of patent 7 years.

To all whom it may concern:

Be it known that I, BYRON B. GOLDSMITH, a citizen of the United States, residing at New York, in the county and State of New York, have invented a new, original, and ornamental Design for Lead-Pencil Tips, of which the following is a specification, reference being had to the accompanying drawing, forming a part thereof.

The figure shows in elevation a lead-pencil tip embodying my design.

I claim—

The ornamental design for a lead-pencil tip, as shown.

BYRON B. GOLDSMITH.
